UNITED STATES PATENT OFFICE.

SAMUEL M. WAGAMAN AND EDGAR H. BYER, OF HAGERSTOWN, MARYLAND; SAID BYER ASSIGNOR TO SAID WAGAMAN.

LOOSE-LEAF BINDER.

1,402,694.

Specification of Letters Patent. Patented Jan. 3, 1922.

Application filed September 8, 1919. Serial No. 322,516.

To all whom it may concern:

Be it known that we, SAMUEL M. WAGAMAN and EDGAR H. BYER, citizens of the United States, residing at Hagerstown, in the county of Washington and State of Maryland, have invented new and useful Improvements in Loose-Leaf Binders, of which the following is a specification.

This invention relates to a loose leaf binder, and some of the objects of the same are to provide a binder of this class wherein the leaf binding elements are in the form of flexible strands, preferably wire, having cooperating locking means directly acting on each strand, the strands being so arranged that the longitudinal tension of each is in the same direction and the stress on the strands or wires is so applied and distributed as to overcome any tendency to looseness or slackness thereof after they have been subjected to the requisite degree of secured tautness, but capable of being readily released when desired; to provide inter-acting loose hinge contact members applied to adjacent parts and so disposed and operating as to effect a tighter binding action of the parts relatively to the leaves when the book is open than when it is closed, and also to effect such an action, together with the strands, upon the leaves of the book when it is closed, as to cause them to project towards the connecting back, in a curved manner, thus simulating the form of the usual tightly bound volume; to provide the leaves with specially formed openings and angularly arranged slots all extending in the same direction from the openings through the inner edges of the leaves to permit the latter to be individually inserted and removed without interfering with the remaining leaves, and to provide a generally improved and comparatively simplified form of loose leaf binding organization comprising parts of a strong and durable structure and that can be readily associated and secured in operative relation and also to duplicate the several parts in form and structure and to arrange them with material advantages in manufacture and essential reduction in the cost of production.

The invention consists in the preferred construction and arrangement of the sev-

eral parts which will be more fully herein-after described and claimed.

In the accompanying drawings one form 55 of the improved loose leaf binder organization is embodied to illustrate a practical assemblage of parts involving the features of the invention but capable of change in the general proportions and contours, as well as 60 in the number of the several parts to adapt the same to various applications. In the accompanying drawings also two sets of leaf engaging and binding strands or wires are shown in cooperation with two sets of 65 similar locking devices at the front and back portions of the binder, but it will be understood that these sets may be diminished or increased in number as may be required in connection with various sizes of 70 the binders.

In the drawings:—

Fig. 1 is a plan view of a binder including a plurality of leaves shown broken away through portions thereof and embodying the 75 features of the invention partially in section.

Fig. 2 is a view similar to Fig. 1 of the reverse side of the binder, which may be either the front or rear side, and also showing parts of the organization in section.

Fig. 3 is a transverse vertical section through a portion of the binder showing one of the cover members open and the other closed.

Fig. 4 is a transverse vertical section of a portion of the binder and loose leaves.

Fig. 5 is a section taken in the plane of the line 5—5, Fig. 3.

Fig. 6 is a section taken in the plane of the line 6—6, Fig. 3.

Figs. 7 and 8 are detail perspective views of the parts of one of the locks.

Fig. 9 is a detail plan view of a portion of one of the loose leaves.

The numerals 5 and 6 respectively represent the covers of the binder connected by a flexible back 7, and forming parts of the improved binder are front and rear fly leaves 8 and 9 which may be of stock of suitable thickness to give them a strong and durable structure sufficient to carry out the functions relatively to the remaining parts of the binder with which they are adapted

to, in a measure, cooperate. Between the fly leaves 8 and 9 a plurality of loose leaves 10 are inserted, each loose leaf having a series of circular openings 11 adjacent to its inner edge, and extending from each opening 11 is an inclined slot 12, all of the slots 12 extending in the same direction, as clearly shown by Figs. 1 and 2. All of the openings 11 and slots 12 are in the same positions in the respective loose leaves 10 so that when the leaves are placed within the binder, the edges thereof will evenly coincide and all the said openings and slots will be in transverse alinement. The slots 12 provide for the insertion and withdrawal of the loose leaves as may be desired relatively to the remaining loose leaves without disturbing or disorganizing the said remaining leaves, and this provision is very advantageous in augmenting the number of leaves containing matter to be preserved within the binder or in replacing certain leaves by others that may embody modified or corrected matter relating to the same or relative subjects.

As hereinbefore indicated, the means directly engaging the loose leaves 10 consist of flexible strands, preferably of wire and it has been found that twisted wire, or wire embodying a plurality of fine strands, similar to what is known as "sash wire", is very well adapted and efficiently serves to hold the leaves in assembled relation. These strands, as shown in the drawings, are in distinct pairs 13 provided by looping a certain length of wire and locating the looped extremity 14 adjacent to one cover and the free ends 15 of the wire strands adjacent to the other cover, the two looped wires being independent, there being two sets of pairs of wire strands in one preferred form of the binder. This number of pairs of wire strands may be reduced or increased as the size of the binder may demand. Each pair 13 of strands is engaged or has in co-operation therewith two locks 17, each lock being composed of the members illustrated by Figs. 7 and 8, or consisting of an elongated box-like enclosure 18 and a clamping lever 19 loosely mounted in the said enclosure without the use of pivots or other securing means. The outer side 20 of each box-like enclosure 18 is substantially fully open and the ends are inwardly bent as at 21 to form terminal closing flanges and adjacent to these terminal closing flanges 21 are inward depending right angular flanges 22 between which and the said terminal flanges 21 guide slots 23 are formed through which the strands 13 are passed. Between the flanges 22 a loose hinge flange 24 is formed, said flange 24 extending beyond the main body of the box-like enclosure and beyond the flanges 22 so as to be free for co-operation with interacting devices which

will be presently described. The terminal flanges 21 are given a slight arcuate shape as clearly shown in the locks illustrated in horizontal section by Figs. 1 and 2. The elongated box-like closures 18 are mounted on metallic wear strips 25 secured to the inner sides of the covers 5 and 6 near the point of engagement or attachment of the inner edges of the covers to the flexible back 7, the metallic wear strips or bars 25 extending lengthwise of the covers a sufficient distance to give proper mounting to these parts, and the elongated box-like closures 18 are provided at their ends with centrally located bendable lugs 26 which are inserted through suitable openings or slots in the bars 25 and upset as clearly shown by Fig. 5. Each lever 19 comprises an elongated clamping bar 27 having a rounded free end 28 and a substantially similar cam end 29 from which a handle or grip 30 extends, the two ends 28 and 29 serving as the clamp terminals relatively to the pairs of strands, there being one lever for each pair of strands, and each lever, as hereinbefore indicated, is loosely held in its elongated box-like enclosure 18, as clearly shown in Figs. 1 and 2. At the outer edge of each box-like enclosure 18 adjacent to the clamping end 28 of the lever is an inwardly bent keeper 31 formed as a part of the top of said box-like enclosure 18, the function of this keeper being to maintain the end 28 of the clamping lever in place when the opposite extremity or end 29 is forced inwardly into or drawn outwardly from the outer open side of the box-like enclosure. It will also be observed that the flanges 22 have their outer edges forming guard walls for the openings 23 and these openings by their location adjacent to the flanged ends 21 of the box-like enclosure cause the strands to be brought into close relation to the said ends 21, and moreover the flanges 22 serve to retain the strands in proper spaced relation at the inner side of each box-like enclosure, the distance between the openings 23 being the same as the distance between the openings 11 in the loose leaves 10. The flanges 21, 22 and 31 all extend inwardly the same distance and their terminal edges contact with the reinforce bar 25, but the inwardly extending angular portion 24^a of the flange or hinge member 24 is of less width than the said flanges 21, 22 and 31 so as to practically cooperate with a complementary flange or locking member 32 at the inner edge of a metal reinforcing strip or bar 33 secured to the adjacent portion of the fly leaf, each fly leaf 8 and 9 having one of the bars 33 secured thereto and each of the bars having two angular flanges or hinge members 32 to cooperate with the flanges 24 of the two box-like enclosures illustrated in the present instance. If the number of

the box-like enclosures be decreased or increased in accordance with the dimensions of the loose leaf binder as a whole, it will be understood that the bars 33 will in like manner have the flanges 32 thereof similarly decreased or increased. The reinforce bars 33 attached to the fly leaves have openings 34 formed therein to accurately register with the openings 11 of the loose leaves and hence these bars 33 perform an important function relatively to the fly leaves in that they prevent wear and tear of the latter and generally strengthen the loose leaf organization embodying the features of the invention. Various means may be employed for securing the bars 25 and 33 respectively to the covers 5 and 6 and fly leaves 8 and 9, and said bars will be of such thickness as to render them strong enough or practically serviceable in performing the functions for which they are used but at the same time thin enough to overcome bulkiness or such projection as would give the improved structure a cumbersome application. It will also be understood that the box-like enclosures 18 for the clamping levers 19 will be minimized as to their surface projection relatively to the parts to which they are attached or will be as flat as possible, and likewise the strands 13 will be of as small diameter as possible consistent with the holding function which they perform relatively to the loose leaves 10.

In applying the strands or wires 13, they are first threaded through the openings 23 of each elongated box-like enclosure 18 and then through the openings 34 of the adjacent fly leaf bar 33 and then carried across and threaded through the openings of the opposite fly leaf bar and the openings 23 of the box-like enclosure on the opposite cover, the said strands being looped with relation to one set of box-like enclosures and having their free ends projecting beyond the opposite set of box-like enclosures. Each pair of strands may be drawn taut or slackened unitedly, for instance, by releasing the clamping lever 19 located adjacent to the looped end of the two strands while the opposite free ends of the strands are held fast by the locking means adjacent thereto, and after the proper adjustment of the strands has been accomplished, the locking lever that has been released will be reset to prevent any slackening or loose movement of the strands. In effecting a locking engagement of each locking lever with the strands with which it is adapted to coact, the free end of the lever 28 is first set against one strand while the lever is in the outer angular position shown by dotted lines in Fig. 2, and after this preliminary placement, the opposite end or heel 29 of the lever is forced inwardly against the strand with which it is to cooperate or impinge, and

these cooperating locking parts will be so proportioned and of such dimensions that the inner edge of each locking lever bar 19 will stand at a slight inclination or will not be parallel with the two flanges 22 as clearly shown by Figs. 1 and 2 whereby a binding lock of greater stress is produced by the two ends of the bar or member 19 of each lever with respect to the strands and owing to the outward curvature of the end flanges 21 of each box-like enclosure, a more effective bite is produced on the portions of the strands engaging said flanges and a more positive retention of the strands within the ends of each box-like enclosure will result.

At any time desired any one or more of the loose leaves 10 may be inserted between other leaves which have been previously engaged by the strands, or may be withdrawn from said previously grouped or engaged loose leaves without disturbing the remaining organization of the several leaves, such insertion and withdrawal being easily effected by reason of the slots 12, all having the same dimensions and being uniform as to their angular positions relatively to the loose leaves.

It is proposed to utilize the improved binder for holding loose leaves containing or having written or printed thereon general information of indiscriminate subjects, but the improved binder is adapted and has been devised especially for use in binding loose leaves embodying medical and other allied subjects.

What is claimed is:—

1. In a loose leaf binder, covers having a connecting back, independent flexible strands extending from one cover to the other to engage and retain loose leaves between the covers, and independent locking levers loosely carried by and freely withdrawable from their applied positions on the covers, the strands being freely slidable in relation to the said levers when the latter are loose and retained in their adjustments by frictional contact of the levers therewith.

2. In a loose leaf binder, covers having a connecting back, independent flexible strands extending from one cover to the other across the inner portion of and free of contact with relation to the said back to engage and retain loose leaves between the covers, and locking means carried by each cover and including loosely mounted levers which independently engage the strands, the strands being passed through the locking means and frictionally retained in association therewith by the said levers, the levers also being held in fixed applied positions by frictional engagement thereof with the strands.

3. In a loose leaf binder, covers having a connecting back, flexible strands arranged in independent pairs to engage and retain

- loose leaves between the covers, and locking means carried by the covers and each including a loose lever frictionally retained therein when applied, the pairs of strands 5 being independently slideable through the locking means and each pair of strands being independently engaged and frictionally held by one of the levers on each of the covers.
- 10 4. In a loose leaf binder, covers having a connecting back, independent pairs of flexible strands extending from one cover to the other to engage and retain loose leaves between the covers, the two strands 15 of each pair being separated, and independent locking means for the two strands of each pair of strands and operating to hold the two strands of each pair in separated relation.
- 20 5. In a loose leaf binder, covers having a connecting back, a looped flexible strand forming two strands, and frames carried by the covers and having loose locking levers for adjustable engagement by the strands and frictionally retaining said strands in the frames and permitting the strands to be simultaneously regulated as to their tension and also holding the strands in positive spaced relation.
- 25 6. In a loose leaf binder, coverings having a connecting back, independent looped flexible strands forming independent pairs of strands extending from one cover to the other to engage and retain loose leaves between the covers, and independent locking means consisting of removably mounted levers, each lever being slidably engaged by each pair of strands and adapted to hold the latter in spaced relation.
- 30 7. In a loose leaf binder, covers having a connecting back, flexible strands extending from one cover to the other, and removable levers having enclosing frames carried by the covers for adjustable engagement by the strands and for holding the latter in parallel spaced relation, the strands being frictionally held by the levers and the latter maintained in their frames by their frictional engagement with the strands.
- 35 8. In a loose leaf binder, covers having a connecting back, flexible strands extending from one cover to the other to retain loose leaves between the covers, and removable locking levers mounted in enclosing frames carried by the covers and having the strands slidably passed therethrough, the strands being adjustable to regulate their tautness by loosening one locking lever and exerting a longitudinal tension simultaneously on the strands while they are held fixed by the locking means on the other 40 cover.
- 45 9. In a loose leaf binder, covers having a connecting back, a looped flexible strand forming two binding strands extending from one cover to the other across and free of back to retain loose leaves between the 50 covers, and removable locking levers having enclosing frames therefor carried by the covers and through which the strands adjustably extend in positive spaced relation, the strands being simultaneously regulable 70 as to their tension by drawing on the looped portion thereof.
- 55 10. In a loose leaf binder, covers having a connecting back, a looped flexible strand forming two strands, and frames carried by the covers and having loose locking levers for adjustable engagement by the strands and frictionally retaining said strands in the frames and permitting the strands to be simultaneously regulated as to their tension and also holding the strands in positive spaced relation.
- 60 11. In a loose leaf binder, covers having a connecting back, independent pairs of flexible strands extending from one cover to the other to engage and retain loose leaves between the covers, and means carried by the covers for engagement by the independent pairs of strands and permitting independent adjustment of the pairs of 85 strands.
- 65 12. In a loose leaf binder, covers having a connecting back, distinct pairs of strands extending from one cover to the other, and means carried by the covers for adjustable 95 engagement by the pairs of strands and permitting the latter to be independently adjusted and also holding them in positive spaced parallel relation.
- 70 13. In a loose leaf binder, covers connected by a back, a pair of flexible strands extending from one cover to the other, and independent locks connected to the covers and each comprising a part removably and frictionally held in place and with which the strands have adjustable engagement.
- 75 14. In a loose leaf binder, covers connected by a looped flexible back, and distinct pairs of flexible strands, lock frames connected to the covers and provided with levers removably and frictionally held therein and adapted to bear on the strands to hold the latter in positive spaced relation to engage and retain loose leaves between the covers.
- 80 15. In a loose leaf binder, covers having a connecting back, flexible strands extending from one cover to the other to retain leaves between the covers, and locking means carried by the covers and consisting of enclosure means having openings adjacent to 115 the ends for slideable and adjustable passage of the strands therethrough, and clamping lever means loosely mounted in the enclosure means and provided with clamping ends to bear on the strands.
- 85 16. In a loose leaf binder, covers having a connecting back, flexible strands extending from one cover to the other to retain leaves between the covers, and locking means held by the covers and consisting of enclosure 120
- 90
- 95
- 100
- 105
- 110
- 115
- 120
- 125

means through opposite extremities of which the strands slidably and adjustably pass, and lever means loosely mounted in the enclosure means and provided with clamping 5 ends to impinge on the strands.

17. In a loose leaf binder, covers having a connecting back, a pair of flexible strands extending from one cover to the other to retain loose leaves between the covers, locking 10 enclosures held by the covers and through which the strands extend in spaced relation and are adjustably held thereby, and levers loosely mounted in the enclosures, one in each, each lever being provided with clamping 15 ends to impinge on the strands.

18. In a loose leaf binder, covers having a connecting back, distinct pairs of flexible strands extending from one cover to the other to retain leaves between the covers, locking 20 enclosures arranged in duplicate in connection with each cover and through which the distinct pairs of strands adjustably extend, the said enclosures being positioned opposite to one another on the respective 25 covers, and a clamping lever loosely mounted in each enclosure and provided with clamping ends to impinge on the strands.

19. In a loose leaf binder, covers having a connecting back and metallic strips secured to the inner sides of the covers adjacent to the point of attachment of the back to the covers, enclosures secured to said strips and disposed opposite to each other on the 35 respective covers, a clamping lever loosely mounted in each enclosure and provided with clamping ends, and pairs of strands inserted through and held in spaced relation in the enclosures, said strands being engaged by 40 the clamping ends of the levers to maintain them in fixed relation to retain loose leaves between the covers.

20. In a loose leaf binder, covers having a connecting back, locking devices carried

by the covers adjacent to the point of attachment of the back thereto, loose leaves held between the covers, and strands engaging the locking means and passing through the inner portions of the loose leaves and also engaged by the locking devices, 45 the locking devices including means operable to primarily adjustably set the strands so that the locking force exerted on the latter is increased when the covers are opened to more firmly bind the leaves.

21. In a loose leaf binder, covers having a connecting back, fly leaves arranged within the covers and having metallic strips with angularly bent flanges, locking means held by the covers and also provided with angularly bent flanges to loosely engage and have a turning movement in relation to the flanges of the said strips on the fly leaves to form loose bracing hinge means, and strands extending from one cover to the other and adjustably engaging the locking 60 means to retain the leaves between the covers and fly leaves.

22. In a loose leaf binder, covers having a connecting back and fly leaves disposed in attached relation thereto, reversely bent flange means held by adjacent portions of the covers and fly leaves, the said reversely bent flange means having loose engagement and turning movement relatively to one 70 another to form bracing hinge means, and means extending from and between the covers for holding and retaining loose leaves between the covers.

In testimony whereof we have hereunto 80 set our hands in presence of two subscribing witnesses.
